Welsh Manufacturing Company, a corpora-
tion of Rhode Island

Application May 7, 1938, Serial No. 77,049

Term of patent 14 years

To all whom it may concern:

Be it known that I, James W. Welsh, a citizen
of the United States, residing at Providence,
county of Providence, and State of Rhode Island,
have invented a new, original, and ornamental
Design for Sunglasses, of which the following is
a specification, reference being had to the accom-
panying drawing, forming a part thereof.

Fig. 1 is a front view;
Fig. 2 is a top plan; and
Fig. 3 is a side elevation of sunglasses showing
my new design.

The dominant features of my design reside in
the curved forward edge of the side shield with
its edge in substantially the plane of the front
and its major portion vertical and following the
temple as shown in full lines.

I claim:

The ornamental design for sunglasses, substan-
tially as shown and described.
